INSULATING STRUCTURE

John J. Garrison, Wellesley, and Stephen Shuko,
Boston, Mass.; said Shuko assignor to said Garrison

Application June 10, 1937, Serial No. 147,470

5 Claims. (Cl. 20—4)

This invention relates to insulating structures and more particularly to a device for supporting insulating material to prevent its sagging and settling. Our device is suitable for supporting 5 all kinds of loose fluffy insulating material whether used for heat insulation or fire and sound retarding.

For heat insulation, for instance, the use of various loosely packed materials, such as kapok, hair, mineral and rock wool, and spun glass is common. These materials depend for their heat insulating qualities upon millions of minute trapped air cells formed within themselves and the efficiency of these materials as heat insulation depends upon maintaining their fluffy and wooly nature, thus insuring the permanent structure of the trapped air cells within them. Such insulating material, however, has a serious tendency to sag or settle because of its own weight, 10 leaving large gaps at the top of the column of insulation and becoming a relatively dense mass at the bottom of the column. Such settling, of course, compresses and destroys the air cells at the bottom of the strip which most effectively 15 resists the transfer of heat and likewise leaves the top of the strip entirely unprotected. This is true whether the insulating material is applied loosely or in the form of bats, or for fire or sound retarding.

Rock wool or like materials to be effective must be placed in position without compression, as compression destroys the air cells and tends to solidify the material. This destroys the heat insulating efficiency of the material while allowing 20 transmission of heat or cold by conduction and also lessens its sound retarding efficiency.

In a co-pending application Serial No. 116,565, filed December 18, 1936, by John J. Garrison as sole inventor, there is described a structure 25 adapted for supporting in the wall of a building a layer of self compressible insulating material, such as rock wool, so as to prevent sagging and settling and maintain the layer substantially in its original fluffy condition. This structure comprises a plurality of light wire frames adapted 30 to be mounted in alinement upon the wall of the building to provide a row extending, for example, from the floor to the ceiling of a given story of the building. Each of these frames carries a shelf structure adapted to be supported in operative position or collapsed for convenience in handling during transit. A small section of the 35 layer of insulating material is supported upon each shelf and extends to the next adjacent shelf.

The present invention contemplates a struc-

ture of this general character which may be installed easily in its operative position but varies in its specific construction. Our device herein is greatly simplified and requires a minimum of stock for its manufacture and, consequently, can 5 be manufactured at low cost. As shown in the drawing, the structure of the invention comprises a light main frame formed from small gauge wire and carrying a plurality of shelf forming members. The structure may be of any 10 desired length such as to support an entire row of sections of insulating material extending from the floor to the ceiling of a given story of a building, but a series of two or more, one suspended from the other, may be used where the distance 15 from the floor to the ceiling is great or for any other reason which renders it desirable. The shelf forming member and the support for holding it in desired operative relation to the main frame, preferably, are such as to cooperate to 20 permit the support to re-enforce and form part of the shelf structure, and to require a minimum of stock to manufacture the same. Our frame also greatly increases the fire retarding qualities 25 of a material like rock wool, because the supporting frame is of wire, a fire resisting material which squarely holds the rock wool in place. Rock wool alone is not effective as a fire stop between the walls unless securely held in place by a fire proof material.

The invention will be more clearly understood 30 from the following description in conjunction with the accompanying drawing, in which:

Fig. 1 is a fragmentary perspective view of a portion of a building containing an insulating structure embodying the invention;

Fig. 2 is a perspective view of a frame structure embodying the invention;

Fig. 3 is a fragmentary perspective view of a modified frame structure embodying the invention, shown folded; and

Fig. 4 is the same as Fig. 3 but with the shelf shown open.

Before explaining in detail the present invention it is to be understood that the invention is 45 not limited in its application to the details of construction and arrangement of parts illustrated in the accompanying drawings, since the invention is capable of other embodiments and of being practiced or carried out in various ways. 50 Also it is to be understood that the phraseology or terminology employed herein is for the purpose of description and not of limitation, and it is not intended to limit the invention claimed herein beyond the requirements of the prior art. 55

A structure embodying the invention is illustrated in Figs. 1 and 2 of the accompanying drawing and comprises a light wire frame 10 having spaced longitudinal members 11. Each of the longitudinal members 11 is preferably provided at intervals with an indentation 12 extending inwardly toward the other longitudinal member and the members 11 are connected at such intervals by cross members 13 which are secured to the longitudinal members 11 as by welding, preferably to the indentations 12. A corresponding pair of indentations 14 are placed on longitudinal members 11 at regular intervals above each indentation 12 and extend inwardly toward each other.

To indentations 12 a U-shaped shelf member 20 is attached having cross portion 21 and having eyes 22 at its free ends which grasp indentations 12 of members 11 and is free to pivot thereon in a vertical plane. Approximately midway of the sides 23 of U-shaped shelf member 20 a pair of indentations 24 are provided therein extending inwardly toward each other.

Depending from indentations 14 of longitudinal members 11 is a second U-shaped member or yoke 25 which acts as a support for shelf member 20, and in part as a support for the insulation itself. Yoke 25 is provided at its free ends with eyes 26 which pivotally engage the corresponding indentations 14 and extend under the shelf 20 when the latter is in extended or horizontal position, yoke 25 engaging shelf 20 at the latter's side indentations 24. It will be noted that the cross portion 27 of yoke 25 is parallel to cross member 13 and cross portion 21 of shelf 20 and therefore serves as part of the supporting shelf structure supporting the insulation material. Eyes 28 are formed in the top ends of longitudinal member 11, by means of which frame 10 may be nailed or otherwise fastened to the wall structure. It will thus be noted that shelf member 20 and supporting member 25, both being pivotally attached to longitudinal members 11, may be folded up and shipped in that condition, thus greatly facilitating packing, and transportation, and reducing space requirements during shipping to a minimum.

In Fig. 3 we have shown a modification in which cross member 13 is eliminated as a separate piece and cross member 13a forms an integral part of shelf 20, loops 22a being formed therein in place of eyes 22 and pivotally engaging longitudinal members 11 at indentations 12 as before. In this way the separate step of welding cross member 13 to longitudinal members 11 at indentations 12 is eliminated. If desired, the free ends 29 of cross member 13a may be welded.

The structure of the invention should have a width corresponding to the spacing of the vertical studs 30 in the wall 31 of a building to permit the frame structure to fit between the studing 30. A close fit is not necessary, as a 12-inch shelf 20, for instance, affords ample platform support for a 14-inch bat of insulation. If desired, however, it is possible to use our structure without any studs whatever and studs 30 may be eliminated, so far as providing support for insulation is concerned. The structure may have any desired length found most convenient in any given circumstances. For example, it may have a length such as to provide in a single structure a plurality of shelf structures 20 dividing the space between the adjacent floors 32 in equal spaces. On the other hand, as illus-

trated in Figs. 1 and 2, if it is desired to have the frames 10 formed in smaller units a number of which may be supported by the one above, eyes 33 may be provided on the lower ends of longitudinal members 11 from which another frame 10 may be supported by means of hooks formed at the top ends of longitudinal members 11 and replacing eyes 28 of the top frame. With a single structure or plurality of structures so supported from the walls 31, sections or bats 35 of insulating material are then placed upon the shelves 20 so as to fill the space between adjacent shelves. It will be noted that the lowermost shelf 20 may be spaced from the floor 32 an amount equal to the distance between adjacent shelves and that the floor 32 may support one of the sections 35. No regular distance between the lowermost shelf 20 and floor is necessary, however, because the bats are easily cut down to fill any irregular space.

The height of each section 35 of insulating material will be determined by the weight and strength of the particular insulating material being used, the proper height being such that the material in each section supports its own weight without sagging or backing down in the section.

It will thus be noted that our open wire frame 10 permits a continuity of the insulating material by providing continuous contact through it, in effect making a solid column of insulation. When a solid material such as wood or metal is used between the insulating material for the purpose of supporting or fastening it and completely separates one section of the material from the other the heat insulating efficiency is greatly impaired by permitting temperature changes through conduction, and the passage of air currents by convection. When the insulating material is properly installed in sections without packing or compression the shelf 20 directly over the material is extended into its horizontal position and supporting member 25 placed under shelf 20, by engaging indentations 24 on shelf 20. The shelf 20 and cross member 27 of supporting member or yoke 25 impinges and seats lightly on the insulating material holding the same in place. It is to be understood that the width of the frame 10 may be made adjustable without departure in any way from the spirit of our invention as shown.

We claim:

1. In an insulating structure for buildings wherein the wall of the building is insulated by a layer of insulating material, in combination, a main frame adapted to be secured to the wall of a building, a skeleton shelf including a pair of arms pivotally connected to said frame, and a U-shaped support having its ends pivotally connected to said frame, said support being adapted to detachably embrace and support said arms in a predetermined angular relation to said frame and serve as an element of said shelf, the arrangement permitting the shelf and its support to be collapsed to substantially flat condition by swinging said arms and support about their pivotal connections with said frame.

2. In an insulating structure for buildings wherein the wall of the building is insulated by a layer of insulating material, in combination, a main frame adapted to be secured to the wall of a building, a skeleton shelf including a pair of arms pivotally connected to said frame, each of said arms having a recess, and a U-shaped support having its ends pivotally connected to said frame, said support normally engaging said re-

cesses and having a portion connecting said arms and serving as an element of said shelf.

3. In an insulating structure for buildings wherein the wall of the building is insulated by a layer of insulating material, in combination, a main frame adapted to be secured to the wall of a building, a pair of U-shaped members having their free ends pivotally connected to said frame to swing about spaced parallel axes to cooperate so that one may engage and support the other as a shelf in a predetermined angular relation to said frame.

4. In an insulating structure for buildings wherein the wall of the building is insulated by a layer of insulating material, in combination, a main frame adapted to be secured to the wall of a building, a U-shaped member pivotally connected at its free ends to said frame and having a recess in each of its parallel portions, and a second U-shaped member having its free ends pivotally connected to said frame at points spaced from the ends of the other U-shaped member and

adapted to engage the recesses on the latter and support the same in a predetermined angular relation to said frame.

5. In an insulating structure for buildings wherein the wall of the building is insulated by a layer of insulating material, in combination, spaced longitudinal frame members provided with correspondingly positioned inwardly extending loops, a transverse frame member extending between and secured to said loops, a pair of U-shaped members, the free ends of one U-shaped member being pivotally connected to said loops and the free ends of the other U-shaped member being pivotally connected to said longitudinal members at points spaced from said loops whereby said U-shaped members may swing so that one may engage and support the other as a shelf in a predetermined angular relation to said frame members.
